UNITED STATES PATENT OFFICE.

LAWRENCE L. SCHAFER, OF WHEELING, WEST VIRGINIA, ASSIGNOR OF ONE-THIRD
TO J. P. SISSON AND ONE-THIRD TO M. J. SMITH, BOTH OF WHEELING, WEST VIR-
GINIA.

LATH SUPPORT.

Application filed March 27, 1925. Serial No. 18,739.

To all whom it may concern:

Be it known that I, LAWRENCE L. SCHAFER, a citizen of the United States of America, and resident of Wheeling, county 5 of Ohio, and State of West Virginia, have invented certain new and useful Improvements in Lath Supports, of which the following is a specification.

This invention relates broadly to lath 10 supports, and more specifically to a stay for unsupported ends of lath contiguous to electrical switch boxes and other boxes of like character.

The primary object of the invention is 15 to provide a simple, durable, efficient and relatively inexpensive device for supporting the unattached extending ends of lath from which short lengths, located between adjacent studding, have been removed for the 20 reception of a switch-box or other similar structure.

The invention, generally considered, consists of a single piece of sheet metal shaped 25 to form a partial enclosure for the unsupported ends of lath and having elongated end portions constituting attaching means, said end portions being adapted to be passed around adjacent full-length lath above and below said unsupported lath ends 30 and to have their terminal portions received within said partial enclosure.

In describing the invention in detail, reference is herein had to the accompanying drawings, in which—

35 Figure 1 is a front elevation of the invention applied at the opposite sides of a switch-box;

Figure 2 is a section on line 2—2, Fig. 1;

40 Figure 3 is an outer side elevation of the invention, detached; and—

Figure 4 is a section on line 4—4, Fig. 3.

Referring to said drawings, 1 indicates a 45 switch-box installed in a recess provided therefor in a building wall, said recess being formed by cutting away sections of one or more laths between adjacent studding 2. The recess so formed has a length, horizontally considered, but slightly greater than suffices to provide accommodation for the 50 box 1, and it ordinarily requires in its formation that sections of two adjacent laths 3 be removed, as shown in Fig. 1. While any suitable form of attaching means for the box 1 may be employed, the necessity

for resorting to the use either of the more 55 or less common metallic mounting strips disposed horizontally above and below the box, or of devices for attaching the box to stays, is obviated. The means herein shown consists simply of lugs 4 carried by the 60 upper and under walls of the box and attachable directly to overlying and underlying full length laths 5 by means of screws 6.

A support or stay for the projecting ends 65 of the laths 3 is disposed adjacent, or in 70 directly abutting relation, to each of the opposite sides of the switch-box 1. Said stay, formed of sheet metal in a single piece, comprises opposite parallel walls 7 and 8 and a back 9 which together form a three- 75 sided enclosure or pocket adapted for the reception of the ends of the lath 3. Said pocket is made of a width approximating the thickness of the laths which it is to accommodate, and has a length approximating the height of the switch-box. The outer wall 7 of the stay has its opposite ends extended to form end portions 7^a, herein-after termed tongues, which are designed to be looped over or about uncut laths 5 located next above and next below the switch-box, and to have their ends inserted within the opposite ends of the lath-receiving pocket between the wall 8 and the adjacent lath ends 3, as in a keeper. 85

The stays serve firmly to maintain the projecting, or floating, ends of the cut laths 3 against displacement with respect to the plane of the lath-formed surface of the building wall, and, further, to maintain the 90 switch-box against movement from its original vertical position. Said stays, abutted by the switch-box, are maintained by the latter against displacement with respect to the laths which they support. 95

While the term "switch-box" is herein employed as designating the box or casing with which the stays are associated, it is to be understood that boxes for housing any of the various forms or types of electrical connections installed in the walls of buildings are intended to be embraced by said term. 100

What is claimed is—

1. A one-piece sheet metal lath stay 105 shaped to form a three-sided pocket for the reception of floating ends of laths, one of the parallel pocket-forming walls being elongated at its opposite ends, forming tongues

adapted to be looped about the laths next above and below the laths whose ends are received in said pocket and to have their ends received in keeper-like spaces between 5 the last mentioned laths and the shorter of said parallel walls.

2. A lath stay for association with a switch-box located within a recess formed by the removal of short sections of laths in 10 a lathed building wall, said stay consisting of a single piece of sheet metal bent to form a three-sided pocket, rectangular in cross-section, adapted to receive therein the floating ends of laths, said stay being adapted

to be positioned within the recess with the 15 back pocket-forming wall thereof abutting a side wall of the switch-box, and one of the parallel pocket-forming walls being extended at opposite ends to form tongues adapted to be looped about the laths next above and below said recess and to have their terminals clamped in place between the shorter of said parallel walls and the floating ends of laths received in said pocket.

In testimony whereof, I affix my signature. 20

LAWRENCE L. SCHAFER.
